UNITED STATES PATENT OFFICE

2,454,004

NAIL POLISH MASK

Norman D. Pettyjohn, Binghamton, N. Y.

Application October 22, 1946, Serial No. 704,818

12 Claims. (Cl. 132—88.5)

1

This invention relates to adjustable nail polish masks.

It is an important object of this invention to provide a mask for protecting adjacent cuticle from polish applied to the finger nail.

It is a further object to provide, in such a mask, facilities for readily effecting adjustments for suiting it for application to fingers of widely differing sizes and forms.

It is a still further object to provide a mask having the foregoing characteristics which will be simple and convenient in operation and capable of inexpensive manufacture.

Other objects will be hereinafter referred to, and still others will be obvious to those skilled in this art during a consideration of the ensuing description in connection with the accompanying drawing, in which:

Figure 1 is a perspective view of a preferred form of the invention, showing, in dotted lines, the outline of a finger in intended position;

Fig. 2 is a longitudinal section approximately along the line 2—2 of Fig. 1;

Fig. 3 is a longitudinal section of one of the turrets, approximately along the line 3—3 of Fig. 1;

Fig. 4 is an enlarged plan view of fragments of the device of Fig. 1 in association with a finger and showing outlines of surfaces of masking pads applied to the finger nail;

Fig. 5 is a top plan view of the device of Fig. 1, on an enlarged scale; and

Fig. 6 is a top plan view of the device of Fig. 5, with certain parts removed.

As best shown in Fig. 1, the frame F has the skirts 21, 21 depending from portions of the respective sides thereof and has an opening 23 therethrough intermediate said skirts for exposing the outer surface of a finger to be treated, when such finger is associated therewith in the manner hereinafter more fully described.

A tab 25 is provided in the wall at one end of the opening 23, and a channel 27 suited for receiving the outer surface of a finger extends along the underside of said frame from the wall at the opposite end of said opening to the end of said frame nearest to said tab. Said tab and channel portion is so relatively formed and positioned that when said channel frame portion is resting upon the outer surface of a finger of the user, the nail of such finger may be placed upon the outer surface of said tab, while the cuticle is positioned beneath the tab, so as to steady the finger during application of polish to the nail, as well as masking the cuticle at the tip of the finger for excluding polish therefrom.

A jaw 29 is attached to the lower side of said frame F by the pivot pin 31 in substantial alignment with said channel portion 27, and a handle 33 associated with said jaw projects by the side

2

of the handle portion 35 carried by said frame F; so that, by pressing said handles 33 and 35 toward one another, said jaw 29 and frame will be spaced apart for receiving a finger therebetween.

A spring 37 urges closure of said jaw 29 against the under-surface of said frame F, for the purpose of firmly retaining a finger therebetween.

A member 41 is disposed substantially parallel with the channel 27, and is secured to the upper surface of said frame F by the guide straps 43, 43, under which said member may freely slide longitudinally of said frame. The bent-over end 41' prevents said member 41 from being fully withdrawn from said straps 43, 43.

A bar 45 is pivotally attached to the member 41 at 47. A masking pad 51 is attached to the end of said bar 45 which extends toward the opening 23, and the opposite end of said bar 45 provides a handle 53 for swinging said pad 51 away from the frame F.

The outer wall 51' of the pad 51 has a convex contour to the end that when said wall is pressed against the ends of the side pads 75, 75, a hereinafter more fully explained, an area at the base of the nail will be masked so as to provide a so-called "half-moon effect."

An extension 55 of the member 41 is associated with the handle 53, and a latch 57 carried by said extension may be engaged by said handle 53 for the purpose of maintaining the pad 51 in elevated position; the construction of the pivotal connection 47 is such as to permit the free end of the handle 53 to be swung into and out of engagement with the latch 57.

A spring 59 urges movement of the bar 45 to carry the pad 51 toward the frame F.

The sliding motion of the member 41 which is permitted by the straps 43, 43 is such that desired positioning of the pad 51 may be effected with relation to any fingernail resting upon the tab 25, irrespective of such variations as may be encountered in the sizes of such nails.

As best shown in Fig. 3, the skirts 21, 21 each have an opening 61 therethrough and carries turret plates 63, 63 at respective sides thereof; said plates having an interconnection 65 therebetween which maintains said plates sufficiently spaced so that they may slide freely over the surfaces of the associated skirt 21.

Each opening 61 is of a size and form which permits movements of the associated interconnection 65 therein incident to various positions of the turret plates 63, 63 connected thereby, for purposes hereinafter more fully explained.

Side bars 67, 67 are mounted on the outer ones of the respective turret plates 63, 63, by means of the pivotal connections 69, 69.

The associated handles 67', 67', the turret extensions 63', 63', the actuating springs 71, 71, and

the latches 73, 73, so nearly correspond with like features hereinbefore described in connection with the longitudinal bar 45 that repetition of such description is deemed unnecessary.

The masking pads 75, 75, are attached to the free ends of the side bars 67, 67.

The pads 51, 75 and 75 are of soft, readily compressible material, such as flexible rubber or a rubber-like compound, and the under-surfaces of said pads are so shaped as to facilitate their conformation to contours of various types of fingernails, when applied thereto as herein-after more fully explained.

Said pads 51, 75, 75 are secured to the carrier arms individual thereto by means of the straps 79; the free ends 81 of associated pairs of said straps being bent somewhat toward one another for better retaining the associated pad therebetween.

As shown, the skirts 21 are disposed at an angle of about 45° from the plane of the device, as exemplified by the axis of the pivot 47 and the surface of the tab 25; but said skirts may be disposed at a greater or less angle, as desired.

Such angular disposition of said skirts not only serves to increase the compactness of the device as a whole, but it also permits the pads 75, 75 to have a front wall substantially perpendicular to the engaging face thereof, which wall will, nevertheless, be disposed at an angle of substantially more than 90° to the general surface of a fingernail to which the pad is applied, and thereby facilitate application of polish thereto.

In using the mask of Fig. 1, the handles 33 and 35 are pressed together, and a finger of the user is inserted along the length of the channel 27, between the lower surface of the frame F and the upper surface of the jaw 29, and the nail of such finger is positioned upon the tab 25, keeping the cuticle below such nail under said tab. The pressure upon the handles 33, 35 is then released, whereupon the spring 37 urges the jaw 29 against the lower surface of the finger which is thereby firmly maintained in position.

The handle 67' of one of the side bars 67 should then be disengaged from its latch 73, and pressed toward the associated turret plate extension 63', and, while so pressed, such turret plate should be moved so that the associated masking pad 75 will have the end thereof farthest from the tab 25 positioned adjacent to the base of the fingernail, and the front face of such pad disposed along the edge of the fingernail so that said pad will cover the adjacent cuticle; whereupon such handle 67' should be released, permitting the spring 71 to press such pad against the cuticle.

The other side bar 67 should then be correspondingly applied to the other side of the fingernail.

After both of the pads 75, 75 have been thus positioned, the handle 53 of the longitudinal bar 45 should be disengaged from its latch 57, and the pad 51 lowered into the plane then occupied by the pads 75, 75; whereupon the bar 45 and the member 41 should be moved toward the opening 23 until the pad 51 presses against the ends of the pads 75, 75, farthest from the tab 25.

Because of the convex contour of the wall 51 of said pad 51, an area at the base of the nail will be masked, in addition to masking the cuticle at the base of the nail, so as to provide a desired "half-moon effect."

Polish may then be applied in the usual or desired manner.

After the polish has hardened, the handle 53 should be pressed toward the extension 55 and secured under the latch 57, and the handles 67', 67', correspondingly manipulated to withdraw the pads 75, 75, from the cuticle around the fingernail.

The handles 33, 35 should then be pressed together, thus swinging the jaw 29 away from the underside of the finger; whereupon the finger

10 may be withdrawn from the mask.

It will be evident that the pad 51 may be integral with either or both of the pads 75, 75, or that such pads may be interconnected by resilient material, to thereby constitute a single structure; and that the various portions of such structure may be attached to bars such as 45, 67, 67, or otherwise, for effecting needful diverse formations and various positionings of such structure, without departing from the general aspects of this invention.

15 It should also be understood that various other changes may be made in the formation and relative positioning of parts, and that parts may be added and/or omitted without departing from the spirit of this invention, in its broader aspects.

20 For example, the user's finger might be held against the upper surface of the frame (instead of the lower surface, as shown). In such an event, a part similar to the jaw 29 would be pivotally attached to the upper side of the frame, and such jaw would also carry pad structure, either directly, or through having a member similar to the bar 45 slidably and pivotally attached to such jaw.

25 It is also to be understood that the language used in the following claims is intended to cover all of the generic and specific features of the invention here described and all statements of the scope of the invention which, as a matter of language, might be said to fall therebetween.

30 Having thus described my invention, what I claim is:

35 1. An adjustable finger mask comprising, in combination, a frame involving provision for supporting a finger of a user in a predetermined longitudinal relationship therewith, levers situated at respective sides of said frame, a lever disposed substantially longitudinally of said frame, masking structure attached to said levers, said structure suited for application to cuticle surrounding a finger nail, and mountings attached to said frame and individual to said levers, said mountings formed and arranged for enabling respectively associated levers to cooperate in effecting various placements of said structure in conformity with cuticle adjacent finger nails of a desired variety of shapes and sizes.

40 2. An adjustable finger mask comprising, in combination, a frame involving provision for supporting a finger of a user in a predetermined longitudinal relationship therewith, levers situated at respective sides of said frame, a lever disposed substantially longitudinally of said frame, masking structure attached to said levers, said structure suited for application to cuticle surrounding a finger nail, mountings attached to said frame and individual to said levers, said mountings formed and arranged for enabling respectively associated levers to cooperate in effecting various placements of said structure in conformity with cuticle adjacent finger nails of a desired variety of shapes and sizes.

45 3. An adjustable finger mask comprising, in combination, a frame involving provision for supporting a finger of a user in a predetermined longitudinal relationship therewith, levers situated at respective sides of said frame, a lever disposed substantially longitudinally of said frame, masking structure attached to said levers, said structure suited for application to cuticle surrounding a finger nail, mountings attached to said frame and individual to said levers, said mountings formed and arranged for enabling respectively associated levers to cooperate in effecting various placements of said structure in conformity with cuticle adjacent finger nails of a desired variety of shapes and sizes, and springs for urging movement of said levers to carry said masking structure toward the position occupied by the nail of a finger supported by said frame.

3. An adjustable finger mask comprising, in combination, a frame involving provision for supporting a finger of a user in a predetermined longitudinal relationship therewith, levers situated at respective sides of said frame, a lever disposed substantially longitudinally of said frame, masking structures attached to said levers, respectively, each of said structures comprising soft, readily compressible material suited for application to cuticle surrounding a finger nail, mountings attached to said frame and individual to said levers, said mountings formed and arranged for enabling respectively associated levers to cooperate in effecting various placements of said structures in conformity with cuticle adjacent finger nails of a desired variety of shapes and sizes, and springs for urging movement of said levers to carry said masking structures toward the position occupied by the nail of a finger supported by said frame.

4. An adjustable finger mask comprising, in combination, a frame involving provision for supporting a finger of a user in a predetermined longitudinal relationship therewith, turret structures associated with said frame at respective sides thereof in a manner permitting free sliding relative movement therebetween, levers pivotally attached to respective turret structures, masking pads carried by ends of said levers, another masking pad of form suited for bridging the space between said first named pads when they are resting upon the cuticle at respective sides of any finger nail of a user, a lever to a free end of which said bridging pad is attached, a carrier member to which said last named lever is pivotally connected, said carrier member secured to said frame in a manner permitting relative movement therebetween in a plane substantially parallel with the length of a finger which is associated with said frame in an intended manner for facilitating various placements of said bridging pad in conformity with a desired variety of finger nail shapes and sizes, and springs urging said levers to move said pads toward said frame.

5. An adjustable finger mask comprising, in combination, a frame having skirts associated therewith at respective sides thereof, turret structures individually associated with said skirts in a manner permitting free sliding relative movement therebetween, levers pivotally attached to respective turret structures, masking pads carried by ends of said levers, another masking pad of form suited for bridging the space between said first named pads when they are resting upon the cuticle at respective sides of any finger nail of a user, a lever to a free end of which said bridging pad is attached, and a carrier member to which said last named lever is pivotally connected, said carrier member secured to said frame in a manner permitting relative movement therebetween in a plane substantially parallel with the length of a finger which is associated with said frame in an intended manner for facilitating various placements of said bridging pad in conformity with a desired variety of finger nail shapes and sizes.

6. An adjustable finger mask comprising, in combination, a frame, turret structures associated with said frame at respective sides thereof in a manner permitting free sliding movement therebetween, levers pivotally attached to respective turret structures, each of said levers having a masking pad carried by an end thereof, another pad of form suited for association with said first named pads when they are resting upon the

cuticle at respective sides of any finger nail of a user for bridging the space therebetween and masking a semi-circular area at the base of such a finger nail, a lever to an end of which said bridging pad is attached, a carrier member to which said last named lever is pivotally connected, said carrier member secured to said frame in a manner permitting relative movement therebetween in a plane substantially parallel with the length of a finger which is associated with said frame in an intended manner for facilitating various placements of said bridging pad to correspond with positionings of said first named pads in conformity with a desired variety of finger nail shapes and sizes, springs urging said levers to move said pads toward said frame, and latches associated with said turret structures and with said carrier member for engaging portions of respectively associated levers for at times preventing such movement.

7. An adjustable finger mask comprising, in combination, a frame having skirts associated therewith at respective sides thereof, a support carried by said frame and suitable for introduction between the end of the nail of a finger and the cuticle thereunder when said finger is positioned intermediate said skirts, turret structures individual to said skirts, each of which turret structures comprises plates at respective sides of the associated skirt and an interconnection between said plates spacing them from the associated skirt to permit free sliding movement therebetween, levers pivotally attached to the outer plates of respective turret structures, each of said levers having a masking pad carried by an end thereof, another pad of form suited for association with said first named pads when they are resting upon the cuticle at respective sides of any finger nail of a user for bridging the space therebetween, a lever to an end of which said bridging pad is attached, a carrier member to which said last named lever is pivotally connected, said carrier member secured to said frame in a manner permitting movement thereof toward and away from said support for facilitating various placements of said bridging pad to correspond with positionings of said first named pads in conformity with a desired variety of finger nail shapes and sizes, and springs urging said levers to move said pads toward said frame.

8. An adjustable finger mask comprising, in combination, a frame having skirts associated therewith at respective sides thereof, each of said skirts having an opening therethrough, a support carried by said frame and suitable for introduction between the end of the nail of a finger and the cuticle thereunder when said finger is positioned intermediate said skirts, turret structures individual to said skirts, each of said turret structures comprising plates at respective sides of the associated skirt and an interconnection between said plates disposed in the skirt-opening and spacing them from the associated skirt to permit free sliding movement therebetween, levers pivotally attached to the outer plates of respective turret structures, each of said levers having a masking pad carried by an end thereof, another pad of form suited for association with said first named pads when they are resting upon the cuticle at respective sides of any finger nail of a user for bridging the space therebetween and masking a semi-circular area at the base of such finger nail, a lever to an end of which said bridging pad is attached, a carrier member to which said last named lever is pivotally connected, said

carrier member secured to said frame in a manner permitting movement thereof toward and away from said support for facilitating various placements of said bridging pad to correspond with positionings of said first named pads in conformity with a desired variety of finger nail shapes and sizes, and springs urging said levers to move said pads toward said frame.

9. An adjustable finger mask comprising, in combination, a frame having skirts associated therewith at respective sides thereof, each of said skirts having an opening therethrough, a support carried by said frame and suitable for introduction between the end of the nail of a finger and the cuticle thereunder when said finger is positioned intermediate said skirts, turret structures individual to said skirts, each of said turret structures comprising plates at respective sides of the associated skirt and an interconnection between said plates disposed in the skirt-opening and spacing said plates from the associated skirt to permit free sliding movement therebetween, levers pivotally attached to the outer plates of respective turret structures, each of said levers having a masking pad carried by an end thereof, another pad of form suited for association with said first named pads when they are resting upon the cuticle at respective sides of any finger nail of a user for bridging the space therebetween and masking a semi-circular area at the base of such finger nail, a lever to an end of which said bridging pad is attached, a carrier member to which said last named lever is pivotally connected, said carrier member secured to said frame in a manner permitting sliding movement thereof in a plane substantially parallel with the length of a finger a nail of which is resting upon said support in an intended manner for facilitating various placements of said bridging pad to correspond with positionings of said first named pads in conformity with a desired variety of finger nail shapes and sizes, springs urging said levers to move said pads toward said frame, and latches associated with said outer turret plates and with said carrier member for engaging portions of respectively associated levers for at times preventing such movement.

10. An adjustable finger mask comprising, in combination, a frame having an opening therethrough of size and shape suited for exposing a finger nail of the user together with the cuticle surrounding such nail, said opening situated intermediate the sides and ends of said frame, a support suitable for introduction between the end of a finger nail and the cuticle thereunder, said support situated at one end of said opening and so formed as to be suited for masking and thereby preventing polish applied to the end of such nail from reaching the cuticle thereunder, said frame having a channel formed in the underside thereof between the other end of said opening and the adjacent end of said frame, a spring urged jaw pivotally attached to the underside of said frame for pressing a finger of the user into said frame channel, means for swinging said jaw away from said frame to release such a finger, skirts associated with said frame at respective sides of said opening, each of said skirts having an opening therethrough, turret structures individual to said skirts, each of said turret structures comprising plates at respective sides of the associated skirt and an interconnection between said plates disposed in the skirt-opening and spacing said plates from the associated skirt to permit free sliding movement therebetween, levers pivotally attached

to respective outer turret plates, masking pads carried by ends of said levers, respectively, a carrier member slidably secured to the outer side of said frame for movement substantially parallel with said channel, a lever pivotally attached to said member, a masking pad attached to an end of said last named lever and suited for bridging the space between said first named pads when they are resting upon the cuticle at respective sides of any finger nail of a user, and springs urging said levers to move said pads toward said frame.

11. An adjustable finger mask comprising, in combination, a frame having an opening therethrough of size and shape suited for exposing a finger nail of the user together with the cuticle surrounding such nail, said opening situated intermediate the sides and ends of said frame, a support suitable for introduction between the end of a finger nail and the cuticle thereunder, said support situated at one end of said opening and so formed as to be suited for masking and thereby preventing polish applied to the end of such nail from reaching the cuticle thereunder, said frame having a channel formed in the underside thereof between the other end of said opening and the adjacent end of said frame, a spring urged jaw pivotally attached to the underside of said frame for pressing a finger of the user into said frame channel, means for swinging said jaw away from said frame to release such a finger, skirts associated with said frame at respective sides of said opening, each of said skirts having an opening therethrough, turret structures individual to said skirts, each of said turret structures comprising plates at respective sides of the associated skirt and an interconnection between said plates disposed in the skirt-opening and spacing said plates from the associated skirt to permit free sliding movement therebetween, levers pivotally attached to respective outer turret plates, masking pads carried by ends of said levers, respectively, a carrier member slidably secured to the outer side of said frame for movement substantially parallel with said channel, a lever pivotally attached to said member, a masking pad attached to an end of said last named lever and suited for bridging the space between said first named pads when they are resting upon the cuticle at respective sides of any finger nail of a user, springs urging said levers to move said pads toward said frame, and latches associated with said outer turret plates and with said carrier member for engaging portions of respectively associated levers for at times preventing such movement.

12. An adjustable finger mask comprising, in combination, a frame having an opening therethrough of size and shape suited for exposing a finger nail of the user together with the cuticle surrounding such nail, said opening situated intermediate the sides and ends of said frame, a support suitable for introduction between the end of a finger nail and the cuticle thereunder, said support situated at one end of said opening and so formed as to be suited for masking and thereby preventing polish applied to the end of such nail from reaching the cuticle thereunder, said frame having a channel formed in the underside thereof between the other end of said opening and the adjacent end of said frame, a spring urged jaw pivotally attached to the underside of said frame for pressing a finger of the user into said frame channel, means for swinging said jaw away from said frame to release such a finger,

skirts associated with said frame at respective sides of said opening, each of said skirts having an opening therethrough, turret structures individual to said skirts, each of said turret structures comprising plates at respective sides of the associated skirt and an interconnection between said plates disposed in the skirt-opening and spacing said plates from the associated skirt to permit free sliding movement therebetween, levers pivotally attached to respective outer turret plates, masking pads carried by ends of said levers, respectively, a carrier member slidably secured to the outer side of said frame for movement substantially parallel with said channel, a lever pivotally attached to said member, a masking pad attached to an end of said last named lever and suited for bridging the space between said first named pads when they are resting upon the cuticle at respective sides of any fingernail of a user, relative formation of parts whereby a portion of said bridging pad will mask a semi-circular area at the base of a

finger nail of the user when said bridging pad rests against portions of said first named pads most remote from said support during positioning of said pads as aforesaid, springs urging said levers to move said pads toward said frame, and latches associated with said outer turret plates and with said carrier member for engaging portions of respectively associated levers for at times preventing such movement.
